(57) **CLAIM**

The ornamental design for a shoe, as shown and described.

DESCRIPTION

FIG. 1 is a front, right side, and top perspective view of a shoe, showing my new design;

FIG. 2 is a rear, left side, and bottom perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof; and,

FIG. 8 is a rear elevation view thereof.

The broken lines shown in the drawings are included for the purpose of illustrating portions of the shoe that form no part of the claimed design.
